UNITED STATES PATENT OFFICE.

PHILIP D'H. DRESSLER, OF ZANESVILLE, OHIO, ASSIGNOR TO AMERICAN DRESSLER TUNNEL KILNS, INC., OF NEW YORK, N. Y., A CORPORATION OF NEW YORK.

COMBINED MUFFLE AND OPEN TUNNEL KILN.

1,360,625.

Specification of Letters Patent. Patented Nov. 30, 1920.

Application filed January 26, 1920. Serial No. 353,976.

To all whom it may concern:

Be it known that I, PHILIP D'H. DRESSLER, a subject of the King of Great Britain, and resident of Zanesville, in the county of Muskingum and State of Ohio, have invented certain new and useful Improvements in Combined Muffle and Open Tunnel Kilns, of which the following is a specification.

10 My present invention relates to continuous tunnel kilns and the general object of the invention is to effect an advantageous combination of constructive features and advantages of the two distinct types of tunnel kilns; one of these two types of tunnel kilns being the open fire type in which all or the major portion of the heating of the goods is accomplished by direct contact of the goods with hot gaseous products of combustion, while the other type is that in which the heating of the goods is accomplished mainly or wholly by convection currents of the kiln chamber atmosphere passing through or along the goods and about 20 combustion chambers in which combustion occurs and from which the products of combustion are withdrawn without passing into the kiln chamber proper and without coming into contact with the goods.

25 The various features of novelty which characterize my invention are pointed out with particularity in the claims annexed to and forming a part of this specification. For a better understanding of the invention, however, and the advantages possessed by it, reference should be had to the accompanying drawings and descriptive matter in which I have illustrated a preferred embodiment of my invention.

30 Of the drawings:

Figure 1 is a somewhat diagrammatic plan of a kiln;

Fig. 2 is a plan of a portion of the apparatus shown in Fig. 1, taken on a larger scale than Fig. 1 and with parts broken away and in section;

Fig. 3 is an elevation in section on the line 3—3 of Fig. 2;

Fig. 4 is an elevation on the section of the line 4—4 of Fig. 2;

Fig. 5 is a view taken similarly to Fig. 1 illustrating a modification;

Fig. 6 is an elevation of a portion of a kiln, illustrating a second modification;

Fig. 7 is a plan of the apparatus shown in Fig. 6;

Fig. 8 is a somewhat diagrammatic plan with parts broken away and in section;

Fig. 9 is a section on the broken line 9—9 of Fig. 8; and

Fig. 10 is a partial section on the line 10—10 of Fig. 8.

In the drawings, and referring first to Figs. 1 to 4, A represents the kiln proper and B, C and D represent successive sections of the kiln chamber. The goods G to be treated are mounted on cars F running on track rails E which extend through the three sections of the tunnel kiln chamber. The goods carrying cars F enter the kiln chamber through the outer end of the section B, which is preferably provided with double doors K and K' forming an air lock. The cars thus entering the kiln are moved slowly through the latter and issue at the outer end of the section D which may advantageously be provided with a door KA. I have not disclosed any mechanism for moving the cars through the tunnel as the details of such mechanism form no part of my present invention, and mechanisms suitable for the purpose are well known and in common use. It will be understood that the tunnel is normally filled with goods carrying cars F, one being taken out of the kiln past the door KA every time a car is inserted in the kiln past the doors K and K'. To prevent the circulation of hot gases along the track rails E and the wheels and other lower parts of the cars F, the well-known expedient may be employed of providing the cars with flanges F' at their sides dipping into sand seals in stationary troughs F².

The intermediate kiln section C is laterally enlarged and horizontally elongated combustion chambers H are located in the lateral enlargement of this kiln section at the sides of the pathway for the goods G. At the ends of the combustion chambers adjacent the outlet door KA fuel gas supply pipes I open into the combustion chambers. Air for the combustion of this gas is admitted to the kiln chamber at the outlet end of the chamber as by means of ports L

formed in the door KA. A draft is created tending to create a gaseous flow from the air inlet ports L at the opposite end of the kiln chamber by suitable means, as for instance, the exhaust fan M shown as connected to the kiln chamber adjacent the door K' by the bifurcated pipe N. To force a large portion of the air thus drawn through the kiln to pass into the combustion chambers 10 H, and through the latter instead of through the clearance space between the goods and the adjacent walls of the kiln chamber section C and combustion chambers H, one or more baffles O are provided at the corresponding ends of the combustion chamber which fit closely about the goods on the cars F. The kiln wall is also advantageously inclined as indicated at C' to facilitate the ready flow of air into the combustion chambers. At the opposite ends of the combustion chambers, the kiln wall is similarly inclined as indicated at C² to avoid eddies and friction impeding the flow out of the combustion chambers and, in practice, the kiln 25 wall at C² should be lined with highly refractory material to avoid deterioration under the high temperatures of the gaseous products leaving the combustion chambers. The combustion chambers are so disposed 30 with respect to the walls of the kiln chamber as to permit the circulation of convection currents upward past the combustion chambers and downward through and along the goods. For this purpose the walls of the 35 combustion chamber may advantageously be formed as in the well-known Dressler kiln of sections of hollow tile. Passages H' in the tile sections unite to form paths of flow about the combustion chambers while at the 40 same time the goods are shielded against the direct radiation of heat from the inside walls of the passages H'.

In operation, the fan M or other draft producing device causes a continuous gaseous 45 flow from the air inlet ports L through the section B of the kiln chamber to the adjacent ends of the combustion chambers H. The air thus brought to the combustion chambers enter the latter and unites in combustion therein with the fuel gas supplied 50 through the fuel gas inlets I. The combustion chamber H should be of such a length, say 20 or 30 feet in ordinary practice that the fuel gas will be entirely burned in the 55 combustion chambers and a large portion of the heat of combustion will be withdrawn from the products of combustion and delivered to the goods through the medium of the convection currents flowing through the passages H' and through or along the goods. 60 The partially cooled products of combustion issuing from the exit end of the combustion chambers pass into the adjacent end of the kiln chambers B and pass longitudinally of the latter to the outlet pipes N. The

products of combustion entering the kiln chamber section B are gradually cooled in their passage through the latter, imparting their heat to the goods G in this section of the kiln. 70

The construction shown in Figs. 1 to 4 is intended for use where the goods after passing through the high temperature zone of the kiln are cooled down to a substantial extent before being taken out of the kiln. 75 This is generally the case, for instance, where the kiln is used in firing pottery. In other cases, however, as for example, in the glass industry and in steel heating furnaces, it is desirable to withdraw the goods from the 80 kilns while still at the maximum temperature attained in the kiln. For such cases the form of my invention illustrated in Fig. 5 is well adapted.

The kiln AA shown in Fig. 5 differs from 85 that shown in Figs. 1 to 4 inclusive essentially in that the cooling section D of the kiln shown in Figs. 1 to 4 is omitted. In Fig. 5 the goods outlet door k is placed immediately adjacent the exit end of the high 90 temperature section C of the kiln, and advantageously a second door ka forming an air lock is provided. The air, uniting in combustion with the gas supplied by the pipes I, is admitted to the combustion chambers 95 through air inlets LA. This air may be drawn directly from the atmosphere or may be preheated as conditions require or make desirable.

Other provisions may be made to direct 100 the flow of air from the kiln section D into the combustion chambers H in lieu of, or in addition to the simple expedient shown in Figs. 1 to 4 of laterally restricting the kiln portion D relative to the kiln portion 105 C and tapering the walls C'. For example, as shown in Figs. 6 and 7 a fan P may have an inlet or inlets P' opening to the kiln section D and its outlet connected by conduits P² to the combustion chambers H in the 110 kiln section CA.

With each of the constructions described I obtain the following characteristic advantages of a kiln having combustion chambers of the Dressler type; namely, the indestructibility of the combustion chambers due to their thin wall construction and the abstraction of heat therefrom by convection currents; the good distribution of heat in the high temperature zone of the kiln resulting from the fact that the heat transfer from the combustion chambers is mainly by convection currents in the fluid medium through which the goods are moved and not by radiation from hot walls or by direct contact with the burning products of combustion; and a sufficiently elongated high temperature zone to permit an adequate exposure of the goods to the highest kiln temperature with a reasonably rapid rate of travel of the goods car- 125 130

rying cars through the tunnel I also obtain the following advantages characteristic of open fire kilns; namely, a shorter length of kiln than is required if substantially all of the heat imparted to the goods is transmitted by conduction through combustion chamber walls; and a cheapening of construction due both to the shortening of the kiln as a whole, and also to the shortening of the combustion chambers relative to the length of the kiln.

In lieu of heating the high temperature zone of a kiln by combustion chambers or muffles, and then passing the partially cooled products of combustion into the kiln chamber proper, I may sometimes, with advantage, heat the high temperature zone of the kiln by combustion occurring in the kiln chamber proper, and then divert the partially cooled products of combustion from the kiln chamber into muffles running along a zone of the kiln maintained at a somewhat lower temperature than the open fire heated high temperature zone of the kiln, and in Figs. 8 to 10 I have illustrated a kiln AB operating in this manner.

The kiln AB comprises a goods cooling zone DB, a high temperature zone CB, and a heating-up zone BB. The goods passing from the high temperature zone CB into the cooling zone DB are subjected in the latter to the cooling action of air drawn into the kiln at its exit end. As shown, the air employed to cool the goods is withdrawn from the zone DB through ports D¹⁰ formed in the kiln roof and pipe Q to which the ports D¹⁰ open. Advantageously the space in the kiln above the pathway for the goods is divided into a series of compartments, open at their lower ends to the goods pathway, by transverse barriers C¹⁰ located one in front of each pair of ports D¹⁰. Heated air escaping from the cooling zone portion of the kiln chamber through the ports D¹⁰ passes into pipes Q and some or all of this air is delivered by fans PA and their outlets P¹⁰ into the ends of the conduits R. The latter run along the high temperature zone CB at opposite sides of the kiln. Conduits D¹¹ deliver air drawn from the compartment at the rear of the baffle C¹⁰ immediately adjacent the high temperature zone of the kiln, into the conduits R. The jets discharged by the fan outlets P¹⁰ create a suction for drawing the air through the conduits D¹¹. The fans PA are thus effective to move air through the conduits D¹¹ without being subjected to the high temperature of this air. The conduits R are provided with vertical outlets R' opening one into each of a series of burner chambers S located at each side of the kiln chamber and distributed along the length of the hot zone CB. Gas is supplied at the outer end of each burner chamber through a corresponding burner pipe IB which extends into

the chamber through the outer wall of the latter and has its outer end connected to a corresponding gas supply pipe or conduit I¹⁰. As shown, the two conduits I¹⁰, one at each side of the kiln, are connected to 70 a source of gas supply I¹¹ which may be a gas holder or a gas producer.

Advantageously, the kiln chamber along the high temperature and cooling zones CB and DB respectively, is laterally restricted 75 to a width little greater than that of the goods carrying cars FB and the goods mounted thereon. Advantageously the goods are so stacked, or the bodies of the cars FB are so formed, as to provide channels F¹⁰ open at their outer ends, and open at their upper sides to the goods above them, and so arranged as to directly receive the jets of flame and burning gases issuing from the different combustion chambers as the movement of the cars carries the channels past the different burner chambers. Advantageously also, the burner chambers and channels F¹⁰ are obliquely inclined to the direction of the movement of 90 the cars as shown in Fig. 8.

The heating-up zone BB of the kiln is laterally enlarged at the sides of the pathway for the goods, to provide spaces for muffles HB extending longitudinally of the 95 kiln at the opposite sides of the portion of the heating-up zone adjacent the high temperature zone. The muffles HB may advantageously be and are shown as being identical in construction and arrangement 100 with the combustion chambers employed in the construction shown in Figs. 1 to 7. The side walls of the kiln are advantageously inclined as indicated at B¹⁰ at the junction between the zones BB and CB to provide 105 an easy path for products of combustion from the hot zone into the muffles HB. Pipes T forming extensions of the muffles HB extend along the sides of the goods pathway through the final portion of the 110 heating-up zone. The ends of these pipes adjacent the ends of the kiln are connected to headers T' having outlet ports N' connected to an exhaust fan M'. The latter creates a positive draft through the muffles 115 HB, and the pipe extensions T of the latter, for drawing the products of combustion into the muffles from the adjacent end of the hot zone CB.

The general mode of operation of apparatus shown in Figs. 8, 9 and 10 will be apparent without further description or illustration. In this apparatus, the goods are in direct contact with the burning gases in the high temperature portion of the kiln. 120 In consequence, the heat abstraction may be very rapid and the length of this portion of the kiln correspondingly reduced. The provision of the muffles HB in the heating-up zone into which the burning gases and 125 130

products of combustion pass prevents the marked and undesirable differences in temperature between the top and bottom of the kiln chamber which would result if the path 5 of travel of the products of combustion through the kiln chamber proper were prolonged to include the heating-up zone of the kiln.

Those skilled in the art will understand 10 that no matter how small the difference between the temperatures at the top and bottom of a kiln chamber at one point along its length may be, if the products of combustion or other hot gases are moved through 15 the kiln chamber away from that point and are cooled in their travel there is a tendency to concentrate a hotter portion of the products or gases along the roof of the cooling chamber and to concentrate a cooler portion along the bottom of the kiln chamber. This stratification which increases, 20 other things being equal, with the distance traveled lengthwise of the kiln, produces a corresponding difference between the temperatures of the top and bottom portions of 25 the goods being heated. The muffles HB, with the open ended passages H' in their walls set up convection currents of the kiln atmosphere in the portion of the kiln chamber in which the muffles are located which prevent marked differences between the temperatures at different levels in the kiln chambers.

It will be understood, of course, that the 35 form of my invention shown in Figs. 8, 9 and 10 is well adapted for use only in burning brick, in heating goods inclosed in saggers, or in heating other goods which are not injured by some local overheating and 40 by direct contact with flames.

The apparatus shown in Figs. 1 to 5 and generically claimed herein is disclosed and claimed more specifically in my earlier application, Serial No. 300,443, filed May 29, 45 1919.

While in accordance with the provisions of the statutes, I have illustrated and described the best form of my invention now known to me, it will be apparent to those 50 skilled in the art that changes may be made in the form of the apparatus disclosed without departing from the spirit of my invention as set forth in the appended claims and that certain features of my invention 55 may sometimes be used to advantage without a corresponding use of other features.

Having now described my invention, what I claim as new, and desire to secure by Letters Patent, is:

60 1. The combination in a tunnel kiln having an elongated kiln chamber comprising two sections placed end to end, of a muffle extending longitudinally of the kiln and located in one of said sections and in communication with the other section at the junc-

tion of the two sections, and air and fuel supply means and products of combustion withdrawing means coöperating to cause the burning gases and products of combustion resulting from combustion of said air and fuel to flow longitudinally of the kiln along a path comprising the interior of the muffle in the one kiln section and the interior of the other kiln section. 70

2. In a combination open fired and muffle heated tunnel kiln the combination with an elongated kiln chamber comprising a laterally restricted portion and a laterally enlarged portion, of a muffle located in said laterally enlarged portion and open to the other kiln portion at its end adjacent the latter, means for supplying fuel and air for its combustion to the kiln and means for withdrawing products of combustion coöperating to cause the burning gases and products of combustion to follow a path of flow extending longitudinally of the kiln chamber, and formed in part by the interior of the muffle and in part by the interior of the restricted kiln chamber portion. 85

3. In a combination open fired and muffle heated tunnel kiln the combination with an elongated kiln chamber comprising two sections placed end to end, means for supplying fuel and air for its combustion to one 95 of said sections, a muffle located in the other section and extending longitudinally of the latter and open at its end adjacent the first mentioned section to the latter, and means for causing products of combustion to pass 100 from the first mentioned section into said muffle.

4. In a combination open fire and muffle heated tunnel kiln the combination with an elongated kiln chamber, of means for supplying fuel and air for its combustion to the interior of one longitudinal section of the kiln, a muffle located in and extending longitudinally of an adjacent section of the kiln and open to the first mentioned kiln 110 section at its end adjacent the latter, and means for withdrawing products of combustion from the end of muffle remote from the first mentioned kiln section.

5. The combination in a tunnel kiln having an elongated kiln chamber comprising two sections placed end to end, of a muffle extending longitudinally of the kiln and located in one of said sections and in communication with the other section at the junction of the two sections, air and fuel supply means and means for withdrawing products of combustion coöperating to cause the burning gases and products of combustion resulting from the combustion of said air 115 and fuel to flow longitudinally of kiln along a path comprising the interior of the muffle in the one kiln section and the interior of the other kiln section, said muffle being formed with open ended passages in 120 125 130

its walls extending transversely of the length of kiln and providing paths for convection currents of the kiln atmosphere upward past the muffle through said passages and downward through a portion of the kiln chamber at the side of the muffle.

6. In a combination open fire and muffle heated kiln, the combination with an elongated kiln chamber comprising two sections placed end to end, means for supplying fuel and air for its combustion to one of said sections, a muffle located in the other section and extending longitudinally of the latter and open at its end adjacent the first men-

tioned section to the latter and means for causing products of combustion to flow from the first mentioned section into and through said muffle, the latter being formed with open ended passages in its wall extending transversely to the length of the kiln and forming paths for convection currents of the kiln atmosphere flowing upward past the muffle and downward through the kiln chamber at the side of the muffle.

Signed at Pittsburgh in the county of Allegheny and State of Pennsylvania this 23rd day of January A. D. 1920.

PHILIP D'H. DRESSLER.
